US0D1046587S

(12) **United States Design Patent** (10) **Patent No.:** **US D1,046,587 S**
(45) **Date of Patent:** **** Oct. 15, 2024**

(54) **WIRE STRIPPER**

(71) Applicant: **Jiangyong Huang**, Sichuan (CN)

(72) Inventor: **Jiangyong Huang**, Sichuan (CN)

(**) Term: **15 Years**

(21) Appl. No.: **29/950,105**

(22) Filed: **Jul. 1, 2024**

(30) **Foreign Application Priority Data**

Jun. 20, 2024 (CN) 202430380332.1

(51) **LOC (14) Cl.** **08-03**

(52) **U.S. Cl.**

USPC **D8/98**

(58) **Field of Classification Search**

USPC ... D8/32, 44, 51, 52, 56, 60, 82, 83, 86, 87, D8/98, 107; D15/127, 129, 139

CPC B23B 27/12; B23B 5/162; B23B 5/165; B23B 5/168; B23B 51/00; B23B 51/04; B23B 51/0426; B23B 51/0453; B25B 15/00; B25B 15/02; B25G 1/085; B27C 5/08; B27M 3/28; C23C 16/4408; C23C 16/45525; C23C 16/45527; C23C 16/4553; C23C 16/52; H01L 21/02164; H01L 21/02274; H01L 21/0228; H02G 1/1204; H02G 1/1212; H02G 1/1214; H02G 1/1224; H02G 1/1226

(57) **CLAIM**

The ornamental design for a wire stripper as shown and described.

DESCRIPTION

FIG. 1 is a front, left and top perspective view of a wire stripper, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged view of detail 9 in FIG. 1.

The dashed broken lines depict portions of the wire stripper that form no part of the claimed design. The dot-dash broken lines in FIGS. 1 and 9 depict the boundaries of the enlargements and form no part of the claimed design.

1 Claim, 9 Drawing Sheets
